UNITED STATES PATENT OFFICE.

HORACE P. SNYDER AND EBENEZER S. BEDFORD, OF GRAND RAPIDS, MICHIGAN; SAID BEDFORD ASSIGNOR OF ONE-HALF HIS RIGHT TO SAID SNYDER.

FOLDING COT.

SPECIFICATION forming part of Letters Patent No. 739,940, dated September 29, 1903.

Application filed October 24, 1902. Serial No. 128,662. (No model.)

To all whom it may concern:

Be it known that we, HORACE P. SNYDER and EBENEZER S. BEDFORD, citizens of the United States, residing at Grand Rapids, in the county of Kent and State of Michigan, have invented certain new and useful Improvements in Convertible Cots, Tents, and Stretchers, of which the following is a specification.

10 Our invention relates to improvements in folding cots; and its objects are, first, to provide a folding cot that may be readily converted into and used as a cot, a stretcher, or a tent; second, to provide a folding cot that 15 may be folded into the least possible compass and be light and convenient to store or carry, and, third, to provide a detachable folding cot with which the canvas stretcher or cot-top may be stretched to any desired tension 20 and will be held rigidly to place. We attain these objects by the mechanism illustrated in the accompanying drawings, in which—

Figure 1 is a top plan of the cot-frame with the canvas top removed. Fig. 2 is a side elevation of the same with the canvas top in place and the tent-supporting frame in position to receive a canvas covering. Fig. 3 is an end elevation of the same. Figs. 4 and 5 are perspectives of the two portions of the 30 connecting joint or knuckle. Figs. 6 and 7 indicate sectional elevations of the side rails, showing the manner of attaching and securing the ends of the revoluble roller or canvas support. Figs. 8 and 9 are plans of the same. Fig. 10 is a plan of one corner of the cot, showing one manner of applying and securing the stationary roll. Fig. 11 indicates an 35 end elevation of one side, showing the leg in its normal position; and Fig. 12 is a side elevation of the same, showing the leg folded.

Similar letters refer to similar parts throughout the several views.

A represents the side bars of our cot-frame, and they are pivoted to the connecting-joints 45 C C', so that they may be made to assume the position indicated by the solid lines for forming the cot-frame or the position indicated by the dotted lines for the purpose of folding the cot preparatory to packing, &c. The

connecting-joint is composed of two disks C 50 and C', which are so connected that they may be readily disconnected upon the line x x of Figs. 1 and 2 for the purpose of reducing the length of the sides, so that they may be conveniently packed and carried. The disk C is 55 provided with an aperture c'', designed to receive the projection c² on the disk C', forming when connected a strong vertical joint that is held in place by the hook c engaging the disk C' at the slotted receptacle c' in such 60 a manner that the disks cannot be drawn apart by downward pressure upon the sides of the frame. The sides of the frame are pivoted to the lugs a, substantially as shown in Figs. 1, 2, and 3, substantially as herein-before described, and to the outer ends of one pair of the side bars A is attached a revoluble support or roller B, which is revolubly secured to the pivotal support H by the bolt or bearing b', and the support is secured to the 70 side bar A by the bolt h, substantially as shown in Fig. 6, so that this roller may be made to form the supporting cross-rail of the cot-frame, or it may be thrown around to the position indicated by the dotted lines in Fig. 1 for 75 folding the frame. The opposite end of this roll is supported in a bearing formed by the standard H', which has a folded leaf at the upper end so arranged that a receptacle is formed between them into which the bearing 80 b'' will enter and revolve freely and is held securely in place by the passage of the pin h'' through the leaf and into the standard, all as shown in Fig. 7. The roller B' is not designed as a revoluble roller, but simply as a cross-girth at the other end of the frame for the support of the side rails and also to receive and support one end of the canvas top E of the cot and may be made an integral part of the pivotal support H, as shown in Fig. 10, or 90 may be attached thereto in any available way.

E represents a canvas or other suitable material top to the cot and is attached by means of the buttons j to the rollers B and B', and to give it the proper tension and strength to support the weight of the occupant of the cot the one end is wrapped once or more around the roller B', and the roller B may be re-

volved by means of the crank *b* until the proper tension is attained, which is retained by means of the pawl *I'*, which is pivoted to the standard *H'*, as at *i*, and has a thumb-
5 piece *i'* at the other end which engages the ratchet *I* upon the end of the roller *B* and acts thereon in the usual manner of operating a pawl and ratchet for the purpose herein set forth. The opposite end of the roller
10 *B'* is supported upon the other side rail of the cot substantially as the corresponding end of the roller *B* is shown to be supported in Fig. 7.

The sockets or leg-supports *D'* are securely attached to and are practically integral with
15 the side rails *A*, to which they are or should be brazed. The legs *D* are pivoted to the lower ends of the sockets by means of a pin or bolt *d'*, which passes through a slot *d* near the end of the legs and so arranged that the
20 leg may be taken, say, at the position indicated in Fig. 11 and drawn down endwise, as indicated by dotted lines, until the upper end will swing clear of the socket, and the leg may be turned around parallel with the side
25 rail *A*, as indicated in Fig. 12, where it is securely held to place by reason of being slid back, so that it has a full and perfect bearing upon the end of the support at both sides of the retaining or pivot pin *d'*. It will be read-
30 ily seen that it makes no difference whether the leg is thrown up parallel with the side rail in direction indicated in Fig. 12 or in the opposite direction. The result is the same.

For the purpose of forming handles for con-
35 verting the cot into a stretcher we pass the tubes *A'* into the ends of the side rails *A*, which are also made of proper tubing and form a slot *a'* in the surface of the handle, which is engaged by the pin *a''* in the side
40 rail, so that the handles may be drawn out to the requisite distance without danger of becoming detached from the cot.

For converting the cot into a tent we form a tent-frame from a large tube *F* and a smaller
45 tube *F'*, which telescopes with the tube *F*, so that it may be extended or shortened, as de-
sired, and pivot standards *G* to these tubes, as at *g'*, so that they may be thrown out, as indicated by the solid lines in Figs. 2 and 3,
50 to form supports for the tent, or they may be folded up parallel with the rods *F* and *F'*, as indicated by the dotted lines, for the purpose of packing the frame in the smallest possible compass. The lower ends of these standards
55 are passed through the apertures *g''* in the slides or handles *A'*, by means of which the tent-frame is supported upon and above the cot, as indicated in Figs. 2 and 3.

Having thus fully described our invention,

what we claim as new, and desire to secure by 60 Letters Patent of the United States, is—

1. In a convertible folding cot, tent and stretcher, a connecting-joint consisting of two disks, one of said disks having a central projection, and a notch in its periphery, the other 65 of said disks having a central opening and a hook on its periphery engaging the projection and notch, respectively, of the other disk, and lugs projecting from the outer surfaces of said disks; in combination with side bars, 70 one end of each of which is pivoted to said lugs giving the opposite ends lateral adjustment, a supporting-roll pivoted to one side bar at each end of the cot, the other end of said rolls detachably connected with the other 75 bars at each end of the cot, one of said rolls revolvably connected at one end with its pivotal support and a pawl-and-ratchet connection between the other bar and the other end of the roll, and folding legs attached to the 80 side bars, substantially as and for the purpose set forth.

2. In a convertible folding cot, tent and stretcher a connecting-joint consisting of two disks, one of said disks having a central projection, and a notch in its periphery, the other 85 of said disks having a central opening, and a hook at its periphery, arranged to engage the projection and notch, respectively, on the other disk, and lugs on the outer surface of 90 said disks; in combination with side bars pivoted at one end to said lugs and the other end adjustable laterally, supporting-rolls at the ends of the cot supported upon the ends of the bars, a flexible top supported thereon, 95 folding legs attached to the side bars, and longitudinally-adjustable handles in the ends of the side bars, substantially as and for the purpose set forth.

3. In combination with the side rails, frame 100 and connecting-joints of a folding cot, down-
wardly-projecting cylindrical sockets secured to the side rails and having downwardly-projecting arms at the sides, cylindrical extensions telescoping into said sockets and having longitudinal slots, and pivot-pins passing through the ends of the socket-arms and the slots in the extensions, said legs adjustable to lock in a vertical or a horizontal position, sub-
stantially as and for the purpose set forth. 110

Signed at Grand Rapids, Michigan, Octo-
ber 18, 1902.

HORACE P. SNYDER.
